TYPE-WRITER.

1,022,673.

Specification of Letters Patent.

Patented Apr. 9, 1912.

Application filed June 28, 1910. Serial No. 569,351.

To all whom it may concern:

Be it known that I, JOHN C. HARTT, a resident of East Liverpool, in the county of Columbiana and State of Ohio, have invented 5 a new and useful Improvement in Type-Writers; and I do hereby declare the following to be a full, clear, and exact description thereof.

My invention relates to typewriters and 10 more particularly to feeding devices therefor adapted to feed envelops or the like into the writing mechanism of the machine. Its object is to provide a device adapted to carry a large number of envelops and to feed the 15 same regularly into proper position for writing without separate hand adjustment of each envelop.

By my invention, I provide means for 20 feeding the envelops or like sheets of paper by simple hand pressure on a rod or like device, as well as means for advancing the envelop one space at a time to allow for writing the subsequent line or lines of the address without interfering with the feeding 25 means for the next succeeding envelop carried by the receptacle. I thereby dispense with a great amount of labor necessary where a large number of envelops are to be addressed in succession, and also enable the 30 work to be done much more quickly.

While I have described my invention as a 35 feeding device for envelops, it will be apparent that the means devised are applicable to other like purposes, and I claim for it all uses to which it is applicable.

To these ends my invention contemplates, generally stated, the combination in a typewriting machine provided with a platen, of suitable line spacing mechanism for actuating 40 the same, the said spacing mechanism being preferably—though not necessarily within the broad scope of my invention,—in the form of a supplementary spacing mechanism detachable from the machine proper, means 45 for carrying a multiplicity of sheets or envelops, mechanism movable by hand pressure to feed said sheets individually to said platen and to engage said line spacing mechanism and thereby advance or actuate 50 said platen to an extent preferably substantially equivalent to the amount of feed. The carrying means for the sheets is preferably embodied in the form of a receptacle attachable to the typewriter carriage of any standard type of machine, and the feeding mecha-

nism is preferably embodied in the shape of a feeding roller carried by the receptacle, with means for maintaining one of the sheets in contact with it, the supplementary line spacing mechanism preferably employed being carried by the receptacle and including a reciprocating bar; another reciprocating bar being arranged to actuate the feed mechanism and also engage with the reciprocating bar of the line spacing mechanism 65 to actuate the same.

In the drawings Figure 1 is a diagrammatic side view of a typewriter illustrating in detail my invention as applied thereto. Fig. 2 is a plan view partly in horizontal 70 section of the device illustrated in Fig. 1. Fig. 3 is a longitudinal section on the line 3—3 Fig. 2. Fig. 4 is a like section showing the feeding device in another position. Fig. 5 is a detail sectional view on the line 5—5 75 Fig. 1. Fig. 6 is a detail sectional view illustrating the ratchet wheel employed; Fig. 7 is a detail side view of the feeding rack rods illustrating a modification; and Fig. 8 is a detail cross section on the line 80 8—8 Fig. 7.

The envelops 1 illustrated are carried in a receptacle 2, into which they may be fed in great quantities as shown, and are maintained in upright position by the follower 85 plate 3. The follower plate 3 is attached to the follower rod 4 which is reciprocally movable in the slot 5, the coiled spring 6 being conveniently arranged around said rod and maintaining the follower plate 3 90 in contact with the envelops with a light pressure. The envelops are preferably “squared” or maintained in even alinement by the adjustment of the movable side 7 of the receptacle 2, the said side 7 being provided at its rear portion with a flange 8 in which is attached a short bolt 9 extending through the slot 10 in the rear wall 11 of the receptacle 2, the side wall 7 being held in any desired position by merely tightening the butterfly nut 12 shown on the bolt 9. The pressure rods 14 carried by the bracket 15 journaled on the swivel 16 are provided to maintain the envelops in substantially even vertical alinement.

The feeding roller or roll 17 extends transversely across the receptacle 2, having journals 18 and 19 in the bearings 20 and 21 attached respectively to the side wall 22 and bottom wall 23 of the receptacle. The 10

roller 17 has preferably a reduced portion 17' to admit of a continuous bottom wall 23 in the receptacle, the said bottom wall 23 being provided with the bracket attachment 24 in its front portion. The slot 25 extends across the receptacle to admit the lower portion of the feeding roller 17 terminating at the reduced portion 17' of said roller as described above. The roller 17 has preferably 10 a roughened surface 17'' which may be provided by wrapping it with emery paper or in any desired fashion.

While the above described arrangement of roller and receptacle bottom is a convenient 15 one, it will be understood that any other construction by which a feeding roller is provided with a slot beneath it and means for maintaining the envelops in contact with said roller and in line with said slot is 20 within the spirit of my invention.

The receptacle 2 can be conveniently mounted on the machine of the type shown, known as the Remington machine, by merely placing the bracket hooks 27 attached to the 25 bottom wall 23 in engagement with the transverse rod 28 of the machine carriage 29, and then attaching the brackets 24 to the rod or T-rail 30 of the machine carriage 29. The bracket hooks 27 are shown as provided with fingers 31 of U-construction, so 30 that they may be arranged on the supporting rod 28 by merely placing the fingers 31 over said rod; and the bracket fastenings 24 are shown as comprising the angle pieces 35 32 and clips 32' which are adapted to firmly grip the T-rail 30 and are fastened thereto by the bolts or thumb screws 33. This construction is specially adapted for use with the Remington typewriter, although it will 40 be understood that by simply varying the attaching devices my invention can be made applicable to any other type of typewriter.

The transverse rod 34 maintains the envelops in proper angular position for feeding 45 through the slot 25 when the roller 17 is actuated by pressure on the rack rod 35. The rack rod 35 is provided with teeth 37 in engagement with the teeth 37' of the ratchet wheel 38 carried on the shaft 39 of the 50 feeding roller 17. The rod 35 is placed at its forward-end within the slot 40 of the bracket 41 attached to the feeding receptacle 2, and at its rear end is provided with the arm 42 adjustably attached to the rod by 55 the screw bolt 42' and provided with the polygonal or in this case squared slot 42'' fitting the squared rod 43. The rod 43 is fixed to the bracket 44 attached to the receptacle 2, and also passes through the slot 45 60 and the bracket lug 46 carried by the ratchet rod 47. The ratchet rod 47 is supported at one end by the rod 46, as just indicated, and at the other end is reciprocally movable within a slot 48' of the bracket 48. The rod 47 65 is provided with ratchet teeth 50 engaging

with like teeth 51 of the ratchet wheel 52. The two movable rods 35 and 47 are thus firmly supported in position by the means described, the bracket rod 43 serving in connection with the arm 42 and lug 46 as a forward support for both rods 35 and 47 and the brackets 41 and 48 serving in connection with the ratchet wheels 38 and 52 to confine the rear portions of both rods 35 and 47 in reciprocally movable position.

The forward motion of both rods 35 and 47 is yieldingly resisted by the compression spring 54 coiled about the rod 43 and engaging with the bracket lug 46 and bracket 44 as shown. The ratchet wheel 38 is journaled on the arbor 56 attached by the bolt 26 to the shaft 39. The arbor 56 carries the ratchet wheel or hub 57, and the pawl 58 carried by the wheel 38 is held in engagement with the teeth of the ratchet hub 57 by the spring 59. The ratchet wheel 52 is of similar construction to the wheel 38, having the ratchet hub 57' rigid with the arbor 56' on which the wheel 52 is journaled and which is attached by the bolt 63' to the shaft 63 rigid with the roller or platen 64 of the typewriter. The pawl 58' and spring 59' are similar in action to the pawl 58 and spring 59. The ratchet wheel 52 may thus be easily substituted for the thumb wheel carried on the shaft of the roller platen of typewriters in use; and in fact my invention, as a whole, can be applied to typewriters now in use without difficulty. The rack bar 47 and the ratchet wheel 52 thus form the essential parts of the supplementary line spacing mechanism attachable to an ordinary typewriter machine. The spring 54 acts to automatically return both the rack bar 47 and the reciprocating bar 35 to initial position, either together, due to the contact of the lug 46 with the arm 42 after the initial feeding operation; or the bar 47 separately when employed in the subsequent advancing or line spacing movement of the 105 platen, as will appear more fully below.

Assuming that the envelops are in position in the receptacle 2 and it is desired to commence the feeding of the same, the rack rod 35 is moved forward by pressure on the button 35' until the adjustable stop 66 strikes the bracket 41. This causes the particular envelop in contact with the feeding roller 17 to be fed into position for typewriting the first line of the address, the envelop passing between the guide roller 67 and guide plate 68 and the typewriting platen 64. The path of the envelop may be further controlled by the guide plate 70 attached to the receptacle 2. By adjusting the position of the stop 66, which feathers in the slot 69 of the ratchet rod 35, the degree of feed may be regulated so as to allow for different sized envelops. In its forward motion the rod 35 carries with it through 110 115 120 125 130

the arm 42 which engages lug 46 the ratchet rod 47 so that the typewriter platen 64 is rotated equivalently to the feeding roller 17, thereby facilitating the feeding of the envelop into typewriting position. This feeding will sometimes result in removing the envelop entirely from the control of the feeding roller 17, depending upon the smallness of the envelop, or its upper portion 10 may still be in contact with the roughened surface of said feeding roller. In this forward motion the lug 71 attached to the ratchet rod 35 contacts with the trigger 72 of the pivoted stop 73 mounted on the sleeve 74 carried on the rod 76 and thereby removes it from the path of the ratchet rod 47. This allows for the full advancement 15 of the ratchet rod 47 and therefore for the rotation of the typewriter platen 64 an amount corresponding to the feed of the roller 17. When the pressure is released from the button 35' both ratchet rods are returned to forward position by the action of the spring 54, the pawls 58 and 58' preventing any communication of retrograde 20 movement to the rollers 17 and 64.

In order to feed the envelop or sheet the space of another line after the first line is written, it is merely necessary to press the button 47' of the ratchet rod 47 and thereby advance the platen roll 64 the required space, the motion of the rod 47 being controlled by the pivoted stop 73. The position of the stop 73 is adjustable on the arm 25 76 of the bracket 77, so that the required spacing may be obtained. The forward motion of the rod 47 is accomplished without disturbing the position of the rod 35 due to the situation of the lug 46 in front 30 of the bracket 42, and the feeding is similar to the ordinary advancing or spacing from line to line of the machine roll or platen. If any of the sheets or envelops are still in contact with the roller 17 they are 35 easily drawn by the platen away from the same. The spring 54 returns the rod 47 to forward position from that illustrated in Fig. 4, and the operation may be repeated if further lines of the address are desired. 40 The envelop may be ejected as illustrated in Fig. 4 in the ordinary manner, the spring plate 78 aiding in maintaining the path of the envelop.

If desired the ordinary line spacing 45 mechanism represented by the rod 80 and levers 81-82 may be employed to advance the sheet after the feeding into position for typewriting of the first line is accomplished, although it is evident that such 50 means as the rack rod 47 is necessary to move the typewriter platen in the first feeding operation, and the push button 47' offers a convenient means for continuing the feeding of the envelop.

55 I regard the provision of feeding mecha-

nism and supplementary line spacing mechanism attachable to an ordinary machine as above indicated as within the scope of my invention. I also regard the arrangement by which the feeding mechanism or rack bar actuating the feeding roller, contacts with the line spacing mechanism to advance the platen simultaneously with the feeding, the spacing mechanism being automatically disengaged 70 from the feeding mechanism to allow the subsequent line spacing, as broadly within the scope of my invention, whether the said line spacing mechanism is supplementary to that employed in a machine of 75 the standard type and detachable therefrom or is itself usually employed in the ordinary line spacing operation of the machine.

Fig. 7 illustrates a modification in which 80 the stop 85 is provided on the rod 47, the said stop being adjustable by means of the screws 86. Where the stop 85 is employed the stopping device including the lug 71 and pivoted stop 73 is dispensed with. On 85 the forward motion of the lower ratchet 47 the stop 85 comes in contact with the bracket 42, and although the upper ratchet rod 45 is forwardly movable it offers sufficient resistance to the light pressure employed on the rod 47 to enable the operator to stop the same. Before one envelop is 90 ejected from the typewriter the follower spring 6 has brought the next succeeding envelop into contact with the roughened feeding roll 17 and the device is in position to feed the next envelop. This operation can be continued until all the envelops are 95 exhausted or they may be replaced as desired. When the necessary quantity has 100 been addressed, the device of my invention can be quickly removed from the machine so that it may be used for ordinary typewriting purposes.

110 What I claim as new is:

1. In typewriters, the combination with a platen, and line spacing mechanism for actuating the same, of means for carrying a multiplicity of sheets, and feeding mechanism adapted to feed said sheets individually to said platen and to engage said line spacing mechanism and actuate the same, the said spacing mechanism being automatically disengageable from said feeding mechanism in the subsequent spacing movement. 115

2. In typewriters, the combination with a platen, of line spacing mechanism including a reciprocating bar movable by hand pressure, means for carrying a multiplicity of sheets, and movable feeding mechanism provided with means for engaging said bar to actuate said line spacing mechanism. 120

3. In typewriters, the combination of a platen, line spacing mechanism including a reciprocating bar independently movable by 125

130

- hand pressure and having a lug, means for carrying a multiplicity of sheets, a feeding roller, and another reciprocating bar adapted to actuate said feeding roller to feed said sheets individually to said platen, and provided with an arm engaging said lug to simultaneously actuate said line spacing mechanism.
4. In typewriters, the combination with a platen, suitable spacing mechanism and a carriage, of a removable attachment comprising a receptacle for sheets or envelopes, supplementary spacing mechanism adapted to actuate said platen, and feeding mechanism adapted to feed the sheets individually thereto, and provided with means for actuating said spacing mechanism simultaneously with said feeding.
5. In typewriters, the combination with a suitable platen, line spacing mechanism and carriage, of a receptacle adapted to carry a multiplicity of sheets, supplementary line spacing mechanism including a reciprocating bar, a feeding roller, another reciprocating bar arranged to actuate the same, and adapted to engage with the aforesaid reciprocating bar to actuate the platen during the feeding of a sheet, the said bars being automatically disengageable to permit the subsequent line spacing movement.
6. In typewriters the combination with a suitable platen and means for advancing the same, of means for carrying a multiplicity of sheets, mechanism for feeding the sheets individually to the platen, and adjustable means for controlling the extent of the feed.
7. In typewriters the combination with a suitable platen and means for advancing the same, of means for carrying a multiplicity of sheets, mechanism for feeding said sheets individually to the platen, a reciprocating bar actuated by hand pressure for actuating said feeding mechanism and adjustable stopping means for controlling the extent of feed.
8. In typewriters, the combination with an impression roller, of a receptacle adapted to carry a multiplicity of sheets, a feeding roller and means for maintaining one of said sheets in contact therewith, mechanism operated by hand pressure to simultaneously actuate said feeding roller and said impression roller to feed the sheet into position for writing the first line, and stopping means for controlling the extent of said feed.
9. In typewriters, the combination with an impression roller, of a receptacle carried on the typewriter carriage and adapted to carry a multiplicity of sheets, a feeding roller adapted to feed one of said sheets at a time, a reciprocating bar and mechanism connecting said bar to each of said rollers whereby a sheet is fed by hand pressure on said bar into position for writing the first or address line.
10. In typewriters, the combination with an impression roller, of a receptacle carried on the typewriter carriage and adapted to carry a multiplicity of sheets, a feeding roller adapted to feed one of said sheets at a time, a reciprocating bar and mechanism connecting said bar to each of said rollers whereby a sheet is fed by hand pressure on said bar into position for writing the first or address line, and an adjustable stop adapted to limit the travel of said bar and vary the position of said first line.
11. In typewriters having an impression roller, a receptacle adapted to carry a multiplicity of sheets or envelopes, a feeding roller and means for maintaining one of said sheets in contact therewith, a ratchet wheel connected to said feeding roller, a rack bar in mesh therewith and a driving connection between said rack bar and said impression roller whereby said feeding roller and said impression roller are simultaneously advanced to feed a sheet into position for writing the first line.
12. In typewriters having an impression roller, a receptacle adapted to carry a multiplicity of sheets or envelopes, a feeding roller and means for maintaining one of said sheets in contact therewith, a ratchet wheel connected to said feeding roller, a rack bar in mesh therewith and a driving connection between said rack bar and said impression roller whereby said feeding roller and said impression roller are simultaneously advanced to feed a sheet into position for writing the first line, means for limiting said feed and means for returning said rack bar to its initial position while said rollers are maintained stationary.
13. An attachment for typewriters comprising a feeding roller, means for carrying a multiplicity of envelopes and for maintaining one of them in contact with said feeding roller, a ratchet wheel connected to said roller and adapted to move the same when moved in one direction and to rotate idly when moved in the opposite direction, a rack bar in mesh with said ratchet wheel, and adjustable means for regulating the travel of said rack bar and thereby varying the extent of feed of said roller.
14. In typewriters, the combination with the typewriter platen and means for advancing the same, of a receptacle adapted to carry a multiplicity of sheets, means for attaching the same to the typewriter carriage, a roller carried by said receptacle, means for maintaining one of said sheets continually in gripping contact with said roller means for rotating said roller, and an adjustable stop adapted to limit the travel of said rotating means.

15. An attachment for typewriters comprising a receptacle adapted to carry a multiplicity of envelops or the like, a feeding roller carried thereby and means for maintaining one of said envelops in gripping contact with said feeding roller, a ratchet wheel connected to said roller, a rack bar in mesh therewith, another ratchet wheel connected to the typewriter platen, another 10 rack bar in mesh therewith, and a connection between said rack bars adapted to actuate said other rack bar when the first mentioned bar is moved but permitting an independent motion of the second mentioned 15 rack bar.
16. An attachment for typewriters comprising a receptacle adapted to carry a multiplicity of envelops or the like a feeding roller carried thereby and means for maintaining one of said envelops in contact therewith, a rack bar, a ratchet wheel in mesh therewith and connected to said feeding roller, another rack bar, and a ratchet wheel in mesh therewith and connected to 20 the typewriter platen, said ratchet wheels being adapted to move said roller and platen respectively when the rack bars are moved forwardly, but having an idle rotation when moved backwardly, an arm carried by one of said bars, a lug carried by the other, and adapted to be moved on the forward motion of said first mentioned bar, and slots in said bar and said lug respectively, a polygonal rod rigidly attached to aforesaid receptacle 25 and fitting into said slots and a spring operative on said lug.
17. An attachment for typewriters comprising a receptacle adapted to carry a multiplicity of envelops or the like, a feeding roller carried thereby and means for maintaining one of said envelops in contact therewith, a rack bar, a ratchet wheel in mesh therewith and connected to said feeding roller, another rack bar, a ratchet wheel in mesh therewith and connected to the typewriter platen, said ratchet wheels being adapted to move said roller and platen respectively when the rack bars are moved forwardly, but having an idle rotation when moved backwardly, means for moving said second mentioned bar when said first mentioned bar is moved forwardly, and automatic means for returning said bars to their initial position.
18. An attachment for typewriters comprising a receptacle adapted to carry a multiplicity of envelops or the like, a feeding roller carried thereby and means for maintaining one of said envelops in contact therewith, a rack bar, a ratchet wheel in mesh therewith and connected to said feeding roller, another rack bar, a ratchet wheel in mesh therewith and connected to the typewriter platen, said ratchet wheels being adapted to move said roller and platen when the rack bars are moved forwardly, 50 but having an idle rotation when moved backwardly, an arm carried by one of said bars, a lug carried by the other and arranged to be moved by said arm on the forward motion of said first mentioned bar and a spring operative on said arm and lug to return said bars to initial position.
19. An attachment for typewriters comprising a receptacle adapted to carry a multiplicity of envelops or the like, a feeding roller carried thereby and means for maintaining one of said envelops in contact therewith, a rack bar, a ratchet wheel in mesh therewith and connected to said feeding roller, another rack bar, a ratchet wheel in mesh therewith and connected to the typewriter platen, said ratchet wheels being adapted to move said roller and platen when the rack bars are moved forwardly, but having an idle rotation when moved backwardly, an arm carried by one of said bars, a lug carried by the other, and adapted to be moved on the forward motion of said first mentioned bar, and slots in said bar and said lug respectively, a polygonal rod rigidly attached to aforesaid receptacle 55 and fitting into said slots and a spring operative on said lug.
20. An attachment for typewriters comprising a receptacle adapted to carry a multiplicity of envelops or the like, a feeding roller carried thereby and means for maintaining one of said envelops in gripping contact with said roller, a ratchet wheel connected to said roller, a rack bar adapted to actuate the same on its forward motion, another ratchet wheel connected to the typewriter platen and a rack bar adapted to actuate the same on its forward motion.
21. An attachment for typewriters comprising a receptacle adapted to carry a multiplicity of envelops or the like, a feeding roller carried thereby and means for maintaining one of said envelops in gripping contact with said roller, a ratchet wheel connected to said roller, a rack bar adapted to actuate said wheel on its forward motion, another ratchet wheel, and a rack bar adapted to actuate the same on its forward motion, a stop adapted to limit the forward motion of said rack bar and means carried by said first mentioned bar for moving said stop out of engaging position with said second mentioned bar on its forward stroke.
22. An attachment for typewriters comprising a receptacle adapted to carry a multiplicity of sheets, a feeding roller carried thereby, and means for maintaining one of said sheets in gripping contact with said roller, a ratchet wheel connected to said roller, a rack bar adapted to actuate the same on its forward motion, another ratchet wheel adapted to be connected to the typewriter platen and a rack bar arranged to actuate the same on its forward motion, adjustable stops adapted to limit the forward motion of each of said bars, and a spring arranged to return them to initial position.

23. An attachment for typewriters comprising a receptacle adapted to carry a multiplicity of envelopes or the like, a feeding roller carried thereby and means for maintaining one of said envelopes in gripping contact with said roller, a ratchet wheel connected to said roller, a rack bar adapted to actuate the same on its forward motion, another ratchet wheel and a rack bar adapted to actuate the same on its forward motion, a trigger stop pivoted to the receptacle and adapted to limit the motion of said second mentioned bar when moved independently, a connection for moving said bar when said first mentioned bar is moved and an arm carried by said first mentioned bar and adapted to remove said trigger stop from the path of said second mentioned bar.
24. In typewriters, the combination with a platen adapted to receive the sheets to be typewritten, of means for carrying a multiplicity of said sheets, a feeding roller adapted to engage said sheets individually and feed the same when actuated to said typewriter platen, mechanism for simultaneously actuating said feeding roller and said platen, said mechanism including means for subsequently actuating said platen to advance a sheet, while maintaining said feeding roller stationary, adjustable means for regulating the travel of said feeding mechanism, and independent means for regulating the travel of said means in-

cluded by said feeding mechanism for independently advancing said typewriter 35 platen.

25. In typewriters, the combination of a platen and reciprocating bar adapted to actuate the same, means for carrying a multiplicity of sheets, a feeding roller arranged 40 to feed said sheets individually to said platen, a reciprocating bar adapted to actuate said feeding roller and provided with means for actuating said first mentioned bar, and means for returning said bars automatically to initial position.

26. In typewriters, the combination of a platen and reciprocating bar adapted to actuate the same, means for carrying a multiplicity of sheets, a feeding roller arranged 50 to feed said sheets individually to said platen, a reciprocating bar adapted to actuate said feeding roller and provided with means for actuating said first mentioned bar, and a spring arranged to be compressed 55 by the forward movement of both of said bars and by said first mentioned bar individually, and adapted to return said bars to initial position.

In testimony whereof, I the said JOHN 60 C. HARTT, have hereunto set my hand.

JOHN C. HARTT.
